CLAIM

The ornamental design for a stove front, as shown and described.

DESCRIPTION

FIG. 1 is a perspective view of a stove front showing our ornamental design;

FIG. 2 is a top view of the stove front shown in FIG. 1;
FIG. 3 is a front view of the stove front shown in FIG. 1;
FIG. 4 is a left side view of the stove front shown in FIG. 1; and,

FIG. 5 is a right side view of the stove front shown in FIG. 1.

The stove front is shown broken away for convenience of illustration in FIGS. 4 and 5.
